JOHN F. STRAUBE, OF ELKHORN, NEBRASKA, ASSIGNOR OF ONE-FOURTH TO NELS SWANSON, OF FREMONT, NEBRASKA

SPIKE-DRAWING DEVICE

Application filed September 28, 1928. Serial No. 308,950.

The invention relates to spike drawing appliances and has for its object to provide a device of this character which will be highly efficient in its operation, especially adapted 5 for drawing railway spikes, and can be economically manufactured.

A further object is to provide a device of this character that will afford a compound application of leverage, which will augment 10 and apply distributed force where it is most needed, and also will conserve the applied energy by the use of pivotal fulcrums so as to eliminate loss thereof through frictional contact of its parts.

15 A further object is to provide a device of this character with interchangeable jaws so as to permit adaptation to various conditions and removal for the purpose of sharpening or repairing.

20 A further object is to provide a device wherein upright posts secured upon a substantial base carry pivotally fulcrumed levers provided with interchangeable spike extracting jaws, and adapted to be forced downwardly by a second lever pivotally fulcrumed 25 between posts mounted upon the rear end of the base; the two levers being connected by a lifting bar pivotally joined to the upper lever and slidably engaging the lower lever 30 so as to bring the jaw into position for engagement below the head of a spike.

With the above and other objects in view the invention resides in the combination and arrangement of parts as hereinafter set forth, 35 shown in the drawing, described and claimed, it being understood that changes in the precise embodiment of the invention may be made within the scope of what is claimed without departing from the spirit of the invention.

In the drawing:

Figure 1 is a top plan view of the device. Figure 2 is a side elevation of the device.

Referring to the drawing, the numeral 1 45 designates the base of a supporting frame comprising upright posts 2 and 3 disposed adjacent the forward end thereof upon transverse brackets 4 and 5, said posts carrying between them a longitudinally disposed lever 6 pivoted on a transverse bolt 7 passing

through the said posts. Disposed upon the end of the said lever adjacent its pivotal point and attached thereto by means of bolts 8 is a spike lifting jaw 9 provided with a flared recess 10 adapted to engage a spike 55 below the head and withdraw it from its setting. Lever 6 extends rearwardly in longitudinal relation to the base 1, between upwardly extending posts 11 and 12, adjacent the rear end of the base 1 upon a transverse 60 footing 13; said posts 11 and 12 have pivotally mounted therebetween at their upper extremity a curved lever 14 which has its pivoted point 15 at the curve in the lever. The lower ends of the braces 16 are connected 65 to bolt 7 thus affording reinforcement against the applied force tending to draw the said post rearwardly. The lower end of the lever 14 is provided with an anti-friction wheel 17 adapted to engage the upper side of the 70 lever 6 when the said lever is moved upwardly and the wheel 17 assumes the position 17^a indicated by the broken lines at the upward extremity of its path, this being the normal position at the beginning of the spike 75 drawing operation. As the lever 14 is moved downwardly the wheel 17 engages the lever 6, which thus receives an amplified force largely in excess of that applied at the end 80 of the said lever 14 by the operator, and this force is further amplified by the second lever 6 which is fulcrumed for a more intensified application of the first force.

A very intense upward force is exerted at the jaws through the compound lever systems 85 which the device affords. Provision for raising the lever 6 simultaneously with an upward movement of the lever 14 is made through the provision of downwardly extending members 23 disposed to the sides of the lever 14, and which downwardly extending members have disposed therebetween a wheel 24 beneath the lever 6 and adapted to lift the lever 6 simultaneously with an upward movement of the lever 14.

The invention having been set forth what is claimed as new and useful is:

A spike drawing device comprising a base, 95 posts mounted upon the forward end of said base, a lever pivotally fulcrumed intermediate 100

the posts, a jaw carried by said lever, posts mounted upon the rear end of said base, a second lever pivotally fulcrumed intermediate the second named posts, wheels rotatably mounted adjacent the lower end of and on said lever and oppositely disposed above and below the first lever and reinforcing bars connecting the fulcrumed pivots of both levers.

10 In testimony whereof I hereunto affix my signature.

JOHN F. STRAUBE.
